CLAIM

The ornamental design for a baby nail trimmer, as shown and described.

DESCRIPTION

FIG. 1 is a front, right and top perspective view of a baby nail trimmer, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front elevation view of FIG. 1 illustrating a cover of the baby nail trimmer removed.

The broken lines shown in the drawings are included for the purpose of illustrating portions of the baby nail trimmer that form no part of the claimed design.
